United States Patent

Des. 241,786
Patented Oct. 5, 1976

241,786

DATA DISPLAY HOLDER OR THE LIKE

Marc E. Berson, 186 N. Woods Drive,
South Orange, N.J. 07079

Filed May 16, 1975, Ser. No. 578,013

Term of patent 14 years

Int. Cl. D20—02

U.S. Cl. D96—2

FIG. 1

FIG. 2

FIG. 3

FIG. 4

FIG. 5

FIG. 6

FIG. 7

FIG. 1 is a front view of a data display holder or the like, incorporating my new design;

FIG. 2 is a left side view thereof;

FIG. 3 is a right side view thereof;

FIG. 4 is a back view thereof;

FIG. 5 is a top view thereof;

FIG. 6 is a bottom view thereof; and

FIG. 7 is a perspective view thereof.

I claim:

The ornamental design for a data display holder or the like, as shown and described.
